TELEPHONE CABLE

Arthur G. Smith, Aldwych, London, England,
assignor to Western Electric Company, Incorporated, New York, N. Y., a corporation of New York

Application April 9, 1932, Serial No. 604,288
In Great Britain May 14, 1931

2 Claims. (Cl. 173—81)

This invention relates to telephone cables and more specifically to the arrangement of conductors in these cables.

In the design of telephone cables difficulty is sometimes found in arranging a specified number of conductors to form a satisfactory cable core or stranding unit owing to the generally adopted practice of twisting the conductors together into groups of 2, 4 or 8 conductors (i. e. pairs, quads and similar units, individually screened or non-screened), before they are stranded to form a cable core. To overcome this difficulty it has been the practice to include in the cable core additional material, so called "fillers" or "fillings" such as paper, jute and similar materials. Alternatively additional conductors of small gauge, either single—that is with earth return—or twisted together in pairs, were used to fill empty spaces in the cable core. When a single conductor has been inserted, an earth return was invariably used, whereby the quality of the circuit was unfavorably affected. In the latter cases the two conductors which compose a circuit, being twisted together, must necessarily be inserted in the same empty space and the gauge is thereby unduly restricted.

In accordance with the present invention, however, the difficulties referred to are overcome by arranging the various conductors which comprise a circuit in different empty spaces of the cable whereby wires of substantial gauge can be used to form high quality circuits of complete metallic returns in addition to those circuits in the main part of the cable.

In order that there may be no interference between two distinct circuits formed by separated conductors when the lines joining the centers of the conductors of the same circuits rotate in the same direction along the cable with the same speed, it is necessary that these center lines be perpendicular to one another.

Thus a stranding unit may comprise a plurality of conductor groups forming pairs, quads, multiple quads or any other assembly of pairs, and between some or all of the conductor groups may be situated two or more single conductors for providing additional circuits.

Figs. 1-12 of the drawings illustrate the manner in which the method of the present invention may be applied and

Fig. 13 is a simplified drawing of a cross-section of a telephone cable disclosing the cable structure.

Fig. 1 illustrates schematically the cross-section of a stranding unit comprising two groups 55 1 and 2, each consisting of a twisted pair, quad,

star or similar structure commonly employed in the construction of telephone cables. Each of the groups may or may not be surrounded by an electrostatic screen. In this figure, a and b are two separated insulated conductors composing a telephone circuit of specified quality. The structure may or may not be served with a wrapping m of paper or the like.

Fig. 2 illustrates three groups 1, 2, 3 similar to those shown in Fig. 1. In this figure, a, b, c, d are four separated conductors forming two and possibly three circuits. The first circuit is composed of a and b, the second of c and d and the third of a and b in parallel and c and d in parallel. The center lines of the circuits a, b and c, d are perpendicular.

Fig. 3 illustrates a modification of the arrangement shown in Fig. 2. In this case a circuit is composed of a and b and a second of a and b in parallel, and c.

Figs. 4, 5, 6, and 7 illustrate arrangements with four, five, six and seven groups 1, 2, 3 . . . 7 similar to those of Fig. 1. In each case there are four separated conductors a, b, c, d used in the manner described. The condition that the center line 25 of the circuit a, b be perpendicular to the center line of circuit c, d is fulfilled in all cases.

Figs. 8 and 9 illustrate arrangements with eight and ten groups 1, 2, 3 . . . 10 similar to those of Fig. 1, the groups being arranged in concentric 30 layers which are stranded in opposite directions. a and b are separated conductors composing a telephone circuit and c, d, e, f are separated conductors composing three additional telephone circuits.

Figs. 10, 11, and 12 illustrate arrangements with eleven, fourteen and nineteen groups 1, 2, 3 . . . 19 similar to those of Fig. 1. Fig. 10 illustrates seven separated conductors a, b, c, d, e, f, g. Figs. 11 and 12 illustrate eight separated conductors a, b, c, d, e, f, g, h from which four physical and two phantom circuits may be obtained. The condition of freedom from interference between circuits is fulfilled in all cases.

A telephone cable may contain one or more of 45 any of the structures illustrated in the Figs. 1-12, or structures built upon the same principle in combination with other units of types generally used in the construction of telephone cables.

Some or all of the conductors in the structures 50 may be loaded in any known manner.

The method described above has particular application to submarine cables where space is especially valuable.

In Fig. 13 has been shown the structure of a 55

cable built in accordance with the method described above. For the sake of simplicity only a single layer of quads has been shown. The quads 20 (which are merely representative of any type 5 of group structure) are arranged in a single layer within an outer covering 21. Placed in interstices between these conductor groups 20 are single conductors 22, 23, 24, and 25 which may or may not be insulated depending on the thickness of the 10 filling between the groups 20 and the size of the conductors 22 to 25, inclusive. Preferably they are made insulated. The center line joining the conductors of circuit 1 (conductors 22 and 24) is at right angles to the center line of circuit 2 (conductors 23 and 25). In this manner interference between the conductors of circuits 1 and 2 is reduced to a minimum.

What is claimed is:

1. A communication cable comprising one or 20 more layers of multi-conductor cable units and single conductors inserted in the interstices between contiguous units within the same layer,

said single conductors being connected so as to form two complete metallic circuits for each layer, the arrangement of said conductors in each layer of said cable being such that a line joining the conductors of one circuit is perpendicular to a line joining the conductors of the other circuit in that layer and such that interference between said circuits is substantially eliminated. 5

2. A communication cable comprising a plurality of oppositely stranded layers of multi-conductor cable units and single conductors inserted in interstices between contiguous units within the same layer, said single conductors being connected so as to form two complete metallic circuits for each layer, the arrangement of said conductors in each layer of said cable being such that a line joining the conductors of one circuit is perpendicular to a line joining the conductors of the other circuit in that layer and such that interference between said circuits is substantially 10 15 eliminated. 20

ARTHUR G. SMITH.
